US0D1015479S

(12) **United States Design Patent** (10) Patent No.: **US D1,015,479 S**
(45) Date of Patent: ** Feb. 20, 2024

(54) **LIVE STREAMING MICROPHONE**

(71) Applicant: **Guoze Qin**, Shanxi (CN)

(72) Inventor: **Guoze Qin**, Shanxi (CN)

(**) Term: **15 Years**

(21) Appl. No.: **29/820,651**

(22) Filed: **Dec. 23, 2021**

(51) LOC (14) Cl. **14-01**

(52) U.S. Cl.

USPC **D14/225**; D14/226

(58) **Field of Classification Search**

USPC D14/225, 226, 228, 229, 217, 188, 192,

D14/252, 253, 496; D13/110; 24/3.12

CPC H04R 25/00; H04R 19/04; H01R 13/44;

H01R 13/60; G06F 1/16

See application file for complete search history.

Primary Examiner — Paula Allen Greene

(57) **CLAIM**

The ornamental design for a live streaming microphone, as shown and described.

DESCRIPTION

FIG. 1 is a perspective view of a live streaming microphone showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another perspective view thereof.

The broken lines throughout the drawing figures depict portions of the live streaming microphone that form no part of the claimed design.

1 Claim, 8 Drawing Sheets
